GEORGE H. HARVEY, OF MIDDLETOWN, OHIO, ASSIGNOR TO THE BLACK-CLAWSON COMPANY, OF HAMILTON, OHIO, A CORPORATION OF OHIO

PAPER-MAKING MACHINE

Application filed August 9, 1926. Serial No. 128,010.

This invention relates to paper-making machinery, and more particularly to paper-making machinery used in the formation of a web or sheet of paper from the paper stock, wherein paper-forming parts are supported 5 between side frames, which forming parts may be provided with and carry an endless conveyor, such as an endless felt, or the like.

One of the principal objects of this invention is to provide a paper-making machine of this character having supporting frames and paper-forming parts carried by said frames, which is so constructed as to permit 10 ready assembly or removal of the paper-forming parts.

Another object of this invention is to provide a paper-making machine of this character having stationary frames for supporting the paper-forming parts, which frames are so constructed as to permit movement of the paper-forming parts into or out of the space intermediate said frames through one of said frames.

Other objects and advantages of this invention will be apparent from the following description when taken in connection with the accompanying drawing.

In the drawing in which like characters of 30 reference designate like parts throughout the several views thereof,

Fig. 1 is a side elevation of a paper-making machine constructed in accordance with this invention;

Fig. 2 is a plan view with certain parts in section of the stationary frames and an associated paper-forming part removed from the space intermediate said frames;

Fig. 3 is a front elevation of the paper-forming part shown in Fig. 2, showing the trucks for supporting said paper-forming part for movement into or out of the space between the frames; and

Fig. 4 is a vertical sectional view on the line 4—4 of Fig. 3, certain parts being broken away to show the construction thereof.

In paper-making machinery designed to form a web or sheet of paper from the paper stock, side frames are usually provided which 50 support the paper-forming parts in operative

position therebetween. Such paper-forming parts may include in the case of a pressing machine, which is customarily positioned immediately after the Fourdrinier so that the web from the delivery end of the Fourdrinier is fed to the first press, an upper press roll, a lower press roll, and the like. For purposes of easy description, the expression "paper-forming part" is used throughout this application to denote any mechanism associated with paper-making machinery of this character which is disposed intermediate side frames in operative position to aid in the manufacture of paper.

As is well known in the paper-making art, paper-forming parts are often of large size and considerable weight, such that much difficulty is experienced in their assembly and disassembly. In paper-making machines as heretofore constructed the disassembly, changing, and assembly of the paper-forming parts is a difficult and tedious task, even for men experienced with their particular machines, and much time is consumed in such procedure due to no adequate provisions being made by the manufacturers of paper-making machinery for such occurrences. This invention provides means for overcoming these objections, by providing a paper-making machine so constructed as to facilitate the assembly and disassembly of the parts.

In the operation of a pressing machine, it is found desirable to remove the soft-surfaced roll of each press from the press and regrind the surface of the roll. The bottom roll of a press is usually the soft-surfaced roll, being faced with rubber or the like, and this roll may be in some cases removed from the press at intervals as frequent as thirty days. This invention is particularly adapted to facilitate the removal of the press rolls for such regrinding or for other purposes; and to facilitate their assembly or installation.

In the drawing this invention is illustrated as applied to a pressing machine, but it is to be understood that the invention is applicable to other types of machines wherein paper-

forming parts are supported in operative position intermediate side frames.

Referring to the drawing, Fig. 1 illustrates a pressing machine equipped with three presses designated 10, 11 and 12 respectively. The number and arrangement of the presses in such a machine is immaterial, as it is apparent that any number and relative arrangement of presses could be provided in accordance with this invention. The construction of the first press 10 is not disclosed in its entirety in the drawing, as it is the same in construction and arrangement as the press 11 which is fully illustrated. Each press consists essentially of an upper press roll 15 and a lower press roll 16. These rolls are of entirely conventional construction; the upper roll being preferably hard-surfaced and constructed of granite or brass and the lower roll being soft-surfaced having a facing of rubber.

In the manufacture of paper when such a machine is assembled and in use, the web from the delivery end of the Fourdrinier is transferred onto an endless carrier felt 20 associated with the first wet press 10, which felt carries the web thus supported through the nip 21 of the press. The felt 20 is provided with a plurality of carrying and supporting pulleys, some of which designated 24 are located within the felt, and others designated 25 are positioned without the felt. A tensioning arrangement 27 is provided for each endless felt. The construction of such tensioning arrangement is not illustrated, as this is entirely conventional and forms no part of the invention. As shown diagrammatically the tensioning arrangement is provided with a tensioning pulley 28 carrying the endless felt, which pulley is supported in a bearing carriage which is adapted to ride up and down on a supporting arm 29 to thus vary the tension of the felt. The movement of the bearing carriage may be obtained by means of a screw threadedly contained by said carriage, so that turning of the screw effects movement of the carriage longitudinally of the screw. For conveniently controlling the tensioning arrangement a hand wheel 30 is provided at the side of the machine, said hand wheel being rigidly fastened on a shaft 31 having a pulley or sprocket wheel 32 which in turn carries a belt or chain 33 cooperating with a second pulley 34 on a shaft 35 associated with the tensioning arrangement. This latter shaft 55 may be provided with a worm which meshes with a pinion on the upper end of the screw, the construction being such that rotation of the hand wheel 30 effects movement of the pulley 28 longitudinally of the arm 29 to vary the tension in the felt.

After passing through the first press, the web of paper is transferred from the felt 20 to an endless felt 40, which carries the web thus supported through the second press. This felt is also provided with a plurality

of carrying and supporting pulleys 24 and 25, and a tensioning pulley 28 associated with tensioning arrangement 27 in a manner similar to the felt 20.

After passing through the second wet press 70 the web is carried by the felt 40 down beneath the third press 12, and is removed from this felt and carried and supported by pulleys 45 and 46 which deliver the web to the side of the press 12 opposite to that at which the web 75 was delivered at the presses 10 and 11. The construction is such that the web is turned over before passing through the third press, in order to partially equalize the pressing effect upon the two sides of the web to give 80 the two sides as nearly the same appearance as possible. A third endless felt 50 is provided for receiving the web just before it enters the nip 51 of the third press. This felt is likewise provided with carrying and supporting pulleys 24 and 25 and a tensioning pulley 28 associated with a tensioning arrangement 27. The web is removed from this felt at 53, and then is carried in the direction as shown by the arrow to further treating devices such 85 as additional presses or driers. This arrangement is conventional and well known in the art, and is described to aid in the understanding 90 of the construction and operation of the machine embodying this invention.

The paper-forming parts of this machine are supported in operative position by means of two side frames designated in Fig. 2 as A and B respectively. In this embodiment of the invention these side frames are made stationary, being bolted to the foundation. In accordance with this invention one of these side frames is provided with an opening or break through which the paper-forming parts may be readily removed or inserted. When such a machine is set up in the plant the driving machinery for driving the paper-forming parts is usually located on one side of the machine called the "drive side." The other side of the machine, which is ordinarily left 100 free of any driving machinery or other obstructions, and from which the operators supervise the operation of the machine is called the "front side." It is obvious that it is more convenient to provide the opening in that side frame which is on the front side of the machine. In Fig. 2 the side frame B is located on the drive side of the machine while the side frame A is located on the front side 110 of the machine, which latter side is the side illustrated in Fig. 1. The side frame A is provided with a plurality of openings or interruptions designated 60, which openings cooperate with the respective presses of the machine. In the machine illustrated one opening 115 is provided for each press. This opening is so associated with its respective press that either of the press rolls can be readily removed from operative position and withdrawn from the space between the side frames 120 125 130.

through this opening, or vice versa inserted through the opening into operative position. The frame in effect has been broken away at points opposite the press rolls of the respective presses, each opening being of sufficient width to permit the rolls as well as a supporting means for the rolls to be moved back and forth through the opening.

The construction of each of the presses is similar, so a description of one of the presses will suffice for all. By providing the opening or interruption in the frame, two supporting standards 62 and 63 remain, one on each side of the opening. Each of these supporting standards has a groove or seat 64 adapted to receive a removable block 65 which carries a bearing standard 66 providing a bearing 67 for one end of the shaft 68 of the lower press roll 16. The frame B as shown in Fig. 2, is provided with a bearing 70 adapted to receive the opposite end of the shaft 68 of the lower press roll. The removable block and bearing carried thereby are so positioned and constructed as to support the shaft in alignment with the bearing 70. Each bearing is provided with a removable cap 69.

The upper press roll 15 is provided with a so-called "lever" support. Each frame (A and B) has an upper standard 75 which carries an arm or lever 76 pivoted at 77 to the standard. At one side of the pivot 77 a bearing 80 is formed in each of the levers, within which the shaft 81 of the upper press roll is journaled. Each bearing 80 is also provided with a removable cap 82. The opposite end of the lever is bifurcated as shown at 87, a rod 88 being carried within the groove so formed. The rod 88 is associated with a ratchet and screw device illustrated diagrammatically at 89, said latter device being provided with a hand lever 90, by means of which the upper press roll may be moved up or down about the pivots 77 to vary its position relative to the lower press roll. By this means the pressure at the nip of the rolls can be conveniently controlled, and also the upper press roll may be readily raised out of contact with the lower press roll or both rolls may be strapped together and raised and lowered by the ratchet device as will be presently described. The bearing end of the lever 75 is provided with a weighting mechanism for maintaining a definite pressure of contact at the nip of the press rolls. This weighting mechanism is shown as comprising a rod 95 fastened at one end to the lever 75, and connected at the other end by means of a hook-and-eye connection 96 to a rod 97 pivoted on a lever 98, which lever carries an adjusting weight 99. In Fig. 1 the parts are shown in operative position with the weighted arm 98 disposed horizontally across the opening 60, the construction serving to exert a constant pull on the end of the lever 75 to maintain a constant pressure at the nip of the press rolls.

A doctor 91 is associated with the upper press roll, the doctor feeding the stock scraped from the roll into a trough 92. The side frames are provided with the usual supports 55 which carry a plank or walk-way 56 and hand-rail 57 to permit the operator to effectively supervise the machine. The side frames are also equipped with steps or foot rests 58 for the same purpose.

In this embodiment of the invention, the lower press roll, which is soft-surfaced, is made removable and means is provided for transporting this roll through the opening 60 in the side frame to the exterior of the machine. Obviously either the upper press roll or lower press roll could be made removable, or both made removable in accordance with this invention.

Positioned beneath each press, and extending through the opening 60 of the frame A, is a track 100. This track comprises two rows of rail-supporting plates 101 which are bolted to the foundation, each row having a rail 102 fastened thereto by screws 103. It is not essential that this track be carried by the foundation, or that the opening 60 extend to the foundation, as the track may be carried in any convenient way below the press rolls. Obviously one of the most convenient ways of supporting the track is on the foundation. Also it is not essential that the tracks 100 and the openings 60 be disposed directly under or opposite the respective presser. A cooperating opening and track can be provided either in advance or behind the press at any convenient point, as the press roll upon removal can readily be transferred by any suitable means from its operative position into position to be removed through the opening. However, the provision of the opening and track beneath the press rolls is particularly convenient and results in that the lower press roll can be easily and readily removed in a novel manner to be presently described.

Cooperating with the track 100 and running thereon are press roll trucks 105. These trucks are adapted to receive the lower press roll, and to support the same during movement away from its operative position. Two supporting trucks are shown, one for each end of the press roll, but obviously any convenient number can be used. Any suitable form of truck can be used, but one that has proven entirely satisfactory for this purpose is disclosed herein.

The construction of this truck is particularly illustrated in Fig. 4. The truck is provided with a supporting frame 110, which has an upper surface 111 corresponding in curvature to the curvature of the press roll. Carried by the upper surface 111 and fastened thereto in any suitable manner is a plurality of wooden blocks or strips 112, these blocks serving to prevent injury to the roll and to firmly support the same thereon.

Each truck is provided at its lower end with two axle-supporting arms 115 and 116 carrying respectively axles 117 and 118. Mounted upon each axle is a wheel structure 120 provided with two grooves 121 and 122 which cooperate respectively with the two rails of the track 100. Positioned between the axle and the wheel structure is a plurality of sets of roller bearings 123 having suitable spacers 124 between them to hold each bearing set in adjusted position. Each end of the axle has a lubricating passage 125 formed with a grease cup 126 at its outer end. The construction provides a freely movable truck, which can be easily moved back and forth upon its cooperating track when carrying the heavy press roll.

With the machine assembled and in operation, when it is desired to disassemble one of the presses and to remove the lower press roll the procedure is as follows:

The bearing caps 69 of each of the bearings of the lower press roll are removed. Metal straps, such as steel straps, are then looped over the projecting journals of the upper and lower press rolls at each end thereof. One of these metal straps is indicated at 130 in Fig. 1, being shown looped over the journals 68 and 81 of the lower and upper press rolls respectively of the press 11. The lever 98 of the weighting mechanism for maintaining the pressure at the nip of the press rolls is then raised to non-operating position and the hook-and-eye connection 96 released. The upper press roll 15 is next raised in its bearings in the lever 75 by means of the ratchet and screw device 89. This takes up the slack in the steel straps, and then both the upper press roll 15 and the lower press roll 16 are raised together upon further actuation of the ratchet and screw device 89. In this manner the lower press roll is raised completely out of its bearings. The removable block 65 carrying the bearing standard 66 is then removed. This part is relatively small and can be easily handled. The felt tensioning device 27 for the felt of this press is so adjusted as to provide plenty of slack in the felt. The portion of the felt beneath the lower press roll is then pulled out through the opening 60 and raised up over the end of the lower press roll. The supporting trucks 105 are pushed in through the opening 60 into position beneath the lower press roll. The ratchet and screw device 89 is then actuated to lower both the upper and lower press rolls until the lower press roll comes to rest upon the supporting trucks 105. The metal straps are removed, and the lower press roll while supported on the trucks is pushed through the opening 60 to the exterior of the press. Upon assembly the procedure is just the reverse of that given above.

While the form of apparatus herein described constitutes a preferred embodiment

of the invention, it is to be understood that the invention is not limited to this precise form of apparatus, and that changes may be made therein without departing from the scope of the invention which is defined in the appended claims.

What is claimed is:

1. In a paper-making machine of the character described, side frames, a foundation supporting said frames, a paper-forming part normally supported in operative position by said side frames, one of said frames having an opening therein extending to said foundation, a track carried by said foundation extending through said opening to the exterior of the machine, and trucks running on said track and adapted to pass through said opening, said trucks being constructed to support said paper-forming part for withdrawal from and insertion into the space intermediate said side frames. 75 80 85

2. A pressing arrangement of the character described comprising an upper press roll, a lower press roll, side frames for normally supporting said press rolls in operative position, one of said frames having an opening therein, and means for moving a press roll through said opening out of or into the space between said side frames. 90

3. A pressing arrangement of the character described comprising an upper press roll, a lower press roll, side frames for normally supporting said press rolls in operative position, one of said frames having an opening therein, a track supported between said frames and extending through said opening to the exterior of the side frame, and trucks running on said track adapted to pass through said opening, said trucks being constructed to support a press roll for withdrawal from and insertion into its operative position intermediate the side frames. 95 100 105

4. A pressing arrangement of the character described comprising an upper press roll, a lower press roll, side frames for normally supporting said press rolls in operative position, one of said frames having an opening therein, a track supported between said frames extending through said opening to the exterior of the side frame, and a truck running on said track adapted to pass through said opening, said truck being constructed to support a press roll for withdrawal from and insertion into its operative position intermediate the side frames, the contacting surface of said truck with the roll being provided with cushioning means to prevent injury to said roll. 110 115 120

5. A pressing arrangement of the character described comprising an upper press roll, a lower press roll, side frames for normally supporting said press rolls in operative position, one of said frames having an opening therein, a track supported between said frames below said lower press roll and ex- 125 130

tending through said opening to the exterior of the side frame, trucks running on said track adapted to pass through said opening, means for raising the upper press roll without removing it from its bearings out of contact with the lower press roll, and means for removing the lower press roll from its bearings and positioning it upon the trucks, said trucks being constructed to support said lower press roll for withdrawal from and insertion into its operative position intermediate the side frame.

6. A pressing arrangement of the character described comprising an upper press roll, a lower press roll, side frames, a lever supported by each side frame, bearings carried by said levers in which the upper press roll is journaled, means for rocking said levers to raise or lower the upper press roll, a lower bearing in one of said frames for one end of the lower press roll, said other frame having an opening therein opposite said last-named bearing, a removable block positioned in said opening, a bearing carried by said removable block for the other end of the lower press roll, and means for moving said lower press roll through said opening into or away from its operative position intermediate said frames when said removable block is removed.

7. A pressing arrangement of the character described comprising an upper press roll, a lower press roll, a side frame on the drive side of said pressing arrangement, a second side frame on the front side of said pressing arrangement, said press rolls being supported in operative position by said frames, said frame on the front side having an opening therein a removable block positioned in said opening, and means for moving a press roll through said opening into or away from its operative position intermediate said frames when said removable block is removed.

8. A pressing arrangement of the character described comprising a plurality of presses, each press having an upper press roll and a lower press roll, side frames for supporting the press rolls of said presses, one of said frames having a plurality of openings therein whereby a cooperating opening is provided for each press, and means for moving a press roll of each press into or out of the space intermediate said frames through its co-operating opening.

9. In a paper-making machine of the character described, a side frame, comprising a stationary part having an opening therethrough and a readily removable part carried by said stationary part, a paper-forming part normally supported in operative position by said removable part, and traveling transporting means for moving said paper-forming part through the said opening

formed in said frame when said removable part is removed.

10. A pressing arrangement of the character described, comprising an upper press roll, a lower press roll, side frames for supporting said press rolls in operative position, one of said side frames including a stationary part having an opening therethrough and a removable part, and traveling means for moving a press roll into or away from its operative position intermediate said frames through the opening formed in said frame when said removable part is removed.

11. A pressing arrangement of the character described, comprising an upper press roll, a lower press roll, side frames for supporting said press rolls in operative position, one of said side frames having an opening therein, transporting means for said lower press roll adapted to move said roll through said opening into or out of the space between said side frames, said transporting means being adapted to be positioned beneath said lower press roll when the same is to be removed, and means for raising said lower press roll from its bearings and for lowering the same into position upon said transporting means.

12. A pressing arrangement of the character described, comprising an upper press roll, a lower press roll, side frames for supporting said press rolls in operative position, one of said side frames having an opening therein, transporting means for said lower press roll adapted to move said roll through said opening into or out of the space between said side frames, said transporting means being adapted to be positioned beneath said lower press roll when the same is to be removed, and means for adjusting the position of said upper press roll, said means being also adapted to raise said lower press roll from its bearings and to lower the same into position upon said transporting means.

13. A pressing arrangement of the character described, comprising an upper press roll, a lower press roll, side frames for supporting said press rolls in operative position, one of said side frames having an opening therein, transporting means for said lower press roll adapted to move said roll through said opening into or out of the space between said side frames, said transporting means being adapted to be positioned beneath said lower press roll when the same is to be removed, means for raising and lowering said upper press roll in its bearings, and strap means for connecting said upper and lower press rolls together for simultaneous movement, the construction being such that said lower press roll is adapted to be raised from its bearings and lowered into position upon said transporting means by said raising and lowering means for the upper press roll.

14. A pressing arrangement of the character

acter described, comprising an upper press roll, a lower press roll, side frames, a lever supported by each side frame, bearings carried by said levers in which the upper press roll is journaled, bearings carried by said side frames in which the lower press roll is journaled, one of said side frames having an opening therein, transporting means for said lower press roll adapted to move said roll through said opening into or out of the space between said side frames, said transporting means being adapted to be positioned beneath said lower press roll when the same is to be removed, means for rocking said levers to raise and lower said upper press roll in its bearings, and strap means adapted to be looped over the journals of said upper and lower press rolls at each end thereof, the construction being such that said lower press roll is adapted to be raised from its bearings and lowered onto said transporting means by said raising and lowering means for the upper press roll.

In testimony whereof I hereto affix my
25 signature.

GEORGE H. HARVEY.
